The ornamental design for a fluid pressure cylinder, as shown.

DESCRIPTION

FIG. 1 is a front, top and left side perspective view of a fluid pressure cylinder showing our new design;

FIG. 2 is a rear, bottom and right side perspective view thereof;

FIG. 3 is a front view thereof;

FIG. 4 is a rear view thereof;

FIG. 5 is a top plan view thereof;

FIG. 6 is a bottom plan view thereof;

FIG. 7 is a left side view thereof;

FIG. 8 is a right side view thereof; and,

FIG. 9 is a cross sectional view taken along the line 9-9 of FIG. 5.
